UNITED STATES PATENT OFFICE.

CLARENCE ERNEST LOMAX, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TESTING SYSTEM.

Application filed September 6, 1921. Serial No. 498,598.

The present invention relates to automatic testing systems in general, but is concerned more particularly with such testing systems as are used in automatic installations which 5 comprise main and branch exchanges; and the principal object briefly stated is the provision of new and improved circuit arrangements and apparatus for systems of this character, whereby a wire chief in a main exchange may test a two way trunk line extending between the main exchange and any branch exchange which may be associated therewith.

Although the present invention is adapted 13 to be used in systems of various sizes it has been chosen to illustrate the same in connection with a system having a nominal capacity of 10,000 lines. In the present system a level, the third for example, of the first 20 or thousands selectors, instead of trunking to regulate second selectors, trunks to a group of special second selectors which have access to ten groups of selector repeaters. Each group of selector repeaters in turn has access 25 to trunk lines of ten branch exchanges. Since there are ten groups of selector repeaters and each group has access through trunk lines to ten branch exchanges, this trunking arrangement provides for 100 30 branch exchanges.

In order to handle the traffic in and out 35 of the branch exchanges, there is provided a group of two way trunk lines between the main and each branch exchange. These trunk lines are seized in the main exchange by the before mentioned selector repeaters and may be seized in the branch exchanges by connector selectors. When one of these 40 trunk lines is seized in the main exchange the normal bridge across the trunk line thereat is cut off and an individual line switch in the branch exchange is operated to pick out an idle connector selector. When one of these trunk lines is seized in the 45 branch exchange, the bridge thereat is cut off and an individual line switch in the main exchange is operated to pick out an idle first selector switch. Now when it is desired to test one of these two way trunk lines it is 50 necessary to seize it at both ends at the same time so as to make it busy at both

ends and also so as to cut off both bridges. The principal feature of the invention, therefore, relates to circuit arrangements and apparatus for accomplishing this result. 55

Referring now to the drawings which comprise Figs. 1 and 2, the apparatus shown in Fig. 1 is assumed to be located in the main exchange while the apparatus shown in Fig. 2 is assumed to be located in one 60 of the branch exchanges.

Referring now particularly to Fig. 1 the automatic switch indicated by the reference character F mechanically is of the type shown in U. S. Letters Patent No. 815,176 65 granted March 13, 1906, to Keith, Erickson, and Erickson; the side switch and private magnet, however, being omitted, and the circuits being modified as shown. This switch is termed a test distributor repeater. 70

The switch indicated by reference character D, which mechanically is of the same type as the switch F, will be referred to hereinafter as a trunk busying switch. The circuits of these two switches D and F are 75 shown complete and will be described fully hereinafter.

The test distributor repeater F, which is directly controlled in both its vertical and its rotary movements, has access to 100 test 80 connectors such as test connector H shown in Fig. 2. This switch, which also is mechanically of the same type as the test distributor repeater F, has access to the local branch exchange lines in the first nine levels 85 of bank contacts and in the tenth level of bank contacts has access to the main to branch exchange trunk lines one of which is the trunk line X. The circuits of this switch are shown complete and will be described fully hereinafter. 90

The trunk line X, which terminates at the main exchange of the line switch C and at the branch exchange in the line switch C', is a two way trunk line and is accessible to 95 the before mentioned selector repeaters in the main exchange at the bank contacts 110—112, inclusive, and their multiples; and is accessible in the branch exchange to the before mentioned connector selectors at the 100 bank contacts 191—193, and their multiples. The selector repeaters referred to may be

mechanically of the same type as the switches D, F, and H and may have circuits substantially the same as are shown in the United States Letters Patent #1,332, 5 217, granted March 2, 1920, to Jacobsen. The connector selectors referred to may be mechanically the same as the selector repeaters and may have circuits substantially the same as are shown in the United States 10 Letters Patent #1,164,479, granted December 4, 1915, to Deakin.

The line switches C and C' are identical and are of the well known rotary type in which the wipers have no normal position 15 and move in a forward direction only.

Reference will now be had to United States Letters Patent No. 1,481,586, granted January 22, 1924, to Benson, which contains a complete disclosure of the necessary equipment 20 for testing the subscribers' lines that terminate in the main exchange. The switches disclosed herein are designed to cooperate with the wire chief's test circuits such as are disclosed in the patent referred 25 to and accordingly the trunk line extending to the test distributor repeater F shown in the present drawings is assumed to terminate at the wire chief's desk in substantially the same manner as the trunk line extending to 30 the test distributor D in the Benson patent referred to.

The system, having thus been described generally, will now be described in connection with a detailed description of the 35 operation of the apparatus shown. For this purpose it will be assumed that the wire chief in the main exchange desires to test the trunk line X.

In order to initiate a test connection the 40 wire chief places a closed loop including the impulse springs of a calling device across the conductors 3 and 4 of the test distributor repeater F. In response to the closure of this bridge line relays 9 and 7 energize and 45 the latter, upon energizing, closes a circuit for repeating relay 12 at armature 28, whereupon the said relay energizes. As a further result of the energization of line relay 7 it 50 closes a circuit for release relay 8 at armature 27. Upon energizing, release relay 8 opens a point in the release magnet circuit at armature 30, at the same time preparing 55 a circuit for the vertical magnet 16, and at armature 29 places ground on release trunk conductor 23. As soon as ground is placed 60 on release trunk conductor 23 a circuit is closed for the lower or polarizing winding of electropolarized relay 13 but this winding alone, consisting of few turns of high resistance, is not able to effectively energize 65 the relay.

The wire chief now operates his calling device in accordance with the first digit of the desired number, thereby interrupting the 70 circuit of line relay 7 a corresponding num-

ber of times. Each time line relay 7 de-energizes in response to one of these interruptions it opens the circuit of repeating relay 12 at armature 28. Repeating relay 12, therefore, falls back each time line relay 7 does but does not perform any function at this time. As a further result of each de-energization of line relay 7 it closes at armature 27 the following circuit: from ground, 75 by way of armature 27 and its resting contact, armature 30 and its working contact, the contact of off normal spring 22 and said spring, series relay 10, and vertical magnet 16 to battery. By the operation of the vertical magnet the switch shaft and wipers are 80 raised step by step until the latter come to rest opposite the level of contacts in which the desired trunk line terminates. Relay 10 is energized in series with the vertical magnet 16 and being slow acting retains 85 its armature attracted throughout the vertical movement, thereby maintaining the circuit of vertical magnet 16 intact after the off normal springs have shifted as they do 90 upon the first vertical step.

At the end of the vertical movement slow acting series relay 10 falls back and at armature 32 shifts the circuit from the vertical to the rotary magnet.

The wire chief now manipulates his calling 95 device in accordance with the second digit of the desired number, whereupon line relay 7 is deenergized a corresponding number of times and, upon each deenergization, completes the following circuit: from ground by 100 way of armature 27 and its resting contact, armature 30 and its working contact, normally open contacts controlled by off normal spring 22, armature 32 and its resting contact, armature 43 and its resting contact, and rotary magnet 17 to battery. By the 105 operation of the rotary magnet the shaft and wipers of the switch F are rotated step by step until the latter come to rest upon the desired set of contacts which we shall assume 110 in this case are the contacts 61-65, inclusive. Slow acting relay 11 is maintained energized in multiple with the rotary magnet 17 throughout the series of interruptions and at 115 armature 33 maintains the test wiper 52 disconnected. At the end of the rotary movement slow acting relay 11 deenergizes and connects up the test wiper 52 at armature 33, thereby completing the following circuit: 120 from ground, by way of release trunk conductor 23, upper winding of switching relay 14, armature 33 and its resting contact, resting contact of armature 39 and said armature, test wiper 52, test contact 62, conductor 66, and relay 101 to battery. Relays 14 and 125 101 energize over the above traced circuit and the latter connects up the private normal conductors of all the trunk lines belonging to the branch exchange in which the 130 trunk line comprising conductors 67-70 in-

clusive, terminates, at armatures 104, 105, and at other armatures which may be provided but which are not shown.

In the switch F, switching relay 14, upon energizing, closes a locking circuit for itself at armature 42; opens the circuit of the rotary magnet 17 at armature 43; places direct ground on test wiper 52 at armature 39; extends the heavy test conductors 2 and 5 at armatures 38 and 44; closes a circuit for the control relay 75 of the trunk busying switch D at armature 41; and at armature 40 places the following bridge across trunk conductors 68 and 69: from conductor 69 by way of bank contact 64, wiper 53, armature 36 and its working contact, upper winding of electropolarized relay 13, armature 40 and its working contact, wiper 51, and bank contact 62 to conductor 68. Current begins to flow through the upper winding of electropolarized relay 13 as soon as this bridge is closed but the said relay is not energized at this time for the reason that the current flowing through the upper winding is opposite in direction to that flowing through the lower winding.

In the branch exchange, line relays 151 and 153 of the test connector H energize in response to the placing of the above traced bridge across the trunk conductors 68 and 69. Line relay 151, upon energizing, closes a circuit for release relay 152 and the latter, upon energizing, prepares a circuit for vertical magnet 166 at armature 163.

Returning now to the trunk busying switch D in the main exchange, we find that control relay 75, upon energizing, in response to the closure of its circuit at armature 41 of switching relay 14, closes a circuit for release relay 76 at armature 86. Release relay 76, upon energizing, prepares a circuit for vertical magnet 80 at armature 88.

The condition that now exists is that the test distributor repeater F has been operated to connect with a test connector located in the branch exchange in which the trunk line that the wire chief desires to test terminates, and the said test connector is ready for operation. Further, the trunk busying switch D in the main exchange is ready to be operated in response to the next digit called.

As it is the usual practice to have all the trunk lines from the main to the branch exchange terminate in the tenth level of the switches at the branch exchange, we shall assume that such is the case in the present system. Accordingly the wire chief manipulates his calling device in accordance with the digit 0, whereupon line relay 7 of switch F is deenergized ten times momentarily and upon each deenergization closes the circuit of slow acting relay 11 at armature 27 and at armature 28 opens the circuit of repeat-

ing relay 12. Each time repeating relay 12 deenergizes it opens the bridge across trunk conductors 68 and 69 at armature 36, and at armature 35 opens the circuit of control relay 75 of the trunk busying switch D. Each time control relay 75 deenergizes it closes at armature 86 the following circuit: from ground by way of armature 86 and its resting contact, armature 88 and its working contact, the contact of off normal spring 94 and said spring, relay 77, and vertical magnet 80 to battery. By the operation of the vertical magnet the shaft and wiper of the switch D are raised step by step until the latter stands opposite the tenth level of bank contacts. Relay 77 is energized in series with vertical magnet 80 and being slow acting retains its armature attracted throughout the vertical movement, thereby maintaining the circuit of the vertical magnet intact after the off normal springs have shifted as they do upon the first vertical step. At the end of the vertical movement slow acting relay 77 deenergizes and transfers the operating circuit from the vertical to the rotary magnet.

In the branch exchange, line relay 151 of the connector H is deenergized ten times momentarily in response to the interruptions produced in its circuit, at armature 36 of repeating relay 12 of test distributor repeater F, and, upon each deenergization, completes the following circuit: from ground and by way of armature 159 and its resting contact, armature 163 and its working contact, the contact of off normal spring 171 and said spring, relay 154, and vertical magnet 166 to battery. By the operation of the vertical magnet the shaft and wipers of the test connector H are raised step by step until the latter stand opposite the desired level of bank contacts which in this case is the tenth. Relay 154 is energized in series with the vertical magnet and being slow acting retains its armature attracted through the vertical movement, thereby maintaining the circuit of the vertical magnet intact after the off normal springs have shifted as they do upon the first vertical step. At the end of the vertical movement slow acting relay 154 deenergizes and at armature 167 transfers the circuit from the vertical to the rotary magnet.

In the main exchange the trunk busying switch D has its wiper 95 stepped up opposite to the tenth level of bank contacts and in the branch exchange the test connector H has its wipers 177-179, inclusive, stepped up opposite the tenth level of bank contacts.

With this condition existing, the wire chief manipulates his calling device in accordance with the digit 1, which is the digit assigned to the trunk line X which he desires to test, whereupon control relay 75 of

the trunk busying switch D and line relay 151 of the test connector H will both be deenergized one time momentarily. Upon deenergizing, the control relay 75 of switch 6 D operates the slow acting series relay 78 and the rotary magnet 81 in series. Rotary magnet 81, upon energizing, advances the switch wiper 95 into engagement with bank contact 96. Slow acting relay 78, upon energizing, disconnects the test wiper 95 at armature 90 and closes a circuit for slow acting relay 79 at armature 91.

At the end of the rotary movement slow acting series relay 78 falls back, connects up the test wiper 95 at armature 90, and at armature 91 opens the initial circuit of slow acting relay 79. This relay in any event, however, being slow acting retains its armature attracted for an interval.

In the branch exchange, line relay 151 of the test connector H, upon deenergizing, operates the slow acting series relay 155 and rotary magnet 175 in series. Rotary magnet 175, upon energizing, advances the wipers 177-179, inclusive, into engagement with the bank contacts 180-182, inclusive, to which the trunk line X is multiplied. Relay 155, upon energizing, disconnects the wipers 177 and 179 at armatures 172 and 176; disconnects the test wiper 178 at armature 168; and at armature 169 opens a point in the circuit of reversing relay 150, at the same time closing the circuit of slow acting relay 156. At the end of the rotary movement slow acting relay 155 deenergizes, connects up the wipers 177 and 179 at armatures 172 and 176; connects up the test wiper at armature 168; and at armature 169 opens the circuit of slow acting relay 156 and closes the circuit of reversing relay 150.

From this point the operation depends upon whether the trunk line X is busy or idle. If it is busy there is a ground potential on the release trunk conductor 183 in 45 the branch exchange and upon release trunk conductor 113 in the main exchange and consequently on the test contact 96 in the bank of the trunk busying switch D. Such being the case slow acting relay 79 of the switch 50 D does not deenergize when its initial circuit is opened at armature 91 by the falling back of slow acting relay 78 but is maintained energized from ground by way of release trunk conductor 113, armature 105 55 and its working contact, conductor 98, bank contact 96, wiper 95, resting contact of armature 90 and said armature, armature 92 and its working contact, and relay 79 to battery.

In the branch exchange slow acting relay 60 156 does not deenergize when its initial circuit is opened at armature 169 of relay 155 but is maintained energized over the following circuit: from ground, by way of release trunk conductor 183, test contact 181,

test wiper 178, armature 164 and its working contact, resting contact of armature 168 and said armature, armature 174 and its working contact, and relay 156 to battery. According to the usual practice the calling 70 wire chief is given reversed battery supervision at this time so as to inform him of the busy condition of the called trunk line. It will be remembered that slow acting relay 155, upon deenergizing, closed the circuit of reversing relay 150 at armature 169 in series 75 with the working contact of armature 173 and the said armature. Upon energizing, reversing relay 150 reverses the incoming 80 trunk conductors 68 and 69, thereby causing 85 a reversal of current flow in the bridge across these conductors including the upper winding of electropolarized relay 13 of the test distributor repeater F. The two windings of electropolarized relay 13 which here- 90 tofore have opposed each other now assist each other in operating the said relay. Upon operating, relay 13 closes at armature 37 the circuit of reversing relay 6 and the 95 said relay, upon energizing, reverses the 100 trunk conductors 3 and 4 with the final result that the busy lamp is lighted before the calling wire chief to inform him of the 105 busy condition of the called line.

The heavy test conductors are now connected with the talking conductors of the trunk line X and the wire chief may associate his head set therewith so as to find out if the trunk line X is actually in use or if it tests busy on account of being out of order. In case the wire chief upon listening in learns that the called trunk line is not in use, he may disassociate his head set from the heavy test conductors and 110 make any desired tests.

Assuming now that the wire chief discovers that the trunk line X is in use he has two courses to follow. He may release the connection and call again later or he may hold up the connection until the trunk line X becomes idle. Assuming that he does the latter, slow acting relay 79 of the trunk busying switch D deenergizes, upon the removal of the ground potential from release 115 trunk conductor 113 of the trunk line X in the main exchange, which occurs as soon as the trunk line becomes idle. As soon as relay 79 deenergizes, it replaces the ground potential on release trunk conductor 113 by 120 way of the following path: from ground, by way of the working contact of armature 87 and said armature, resting contact of armature 92 and the said armature, and thence by way of a previously traced 125 circuit to release trunk conductor 113. As soon as this ground potential is replaced switching relay 114 of line switch C energizes in series with stepping magnet 115 but the said stepping magnet is 130 not energized on account of the high resist-

ance of switching relay 114. Relay 114, upon energizing, disconnects the upper and lower conductors of the trunk line X from the winding of line relay 116 and from ground at armatures 117 and 118, respectively, but owing to a mechanical interlocking device (not shown) between the armature of said relay and the armature of line relay 116, the armature of switching relay 114 is not completely operated at this time and consequently the switch wipers 119-121, inclusive, are not connected up.

In the branch exchange, slow acting relay 156 upon deenergizing in response to the removal of the ground potential from release trunk conductor 183, opens the circuit of reversing relay 150 at armature 173, and at armature 174 replaces the ground potential on release trunk conductor 183, whereupon switching relay 184 in the line switch C' pulls part way up and removes battery and ground from the upper and lower conductors of the trunk line X, respectively. Reversing relay 150, upon deenergizing in response to the opening of its circuit at armature 173 of relay 156, reverses trunk conductors 68 and 69 back to normal, whereupon electro-polarized relay 13 of the test distributor repeater F retracts its armature, thereby opening the circuit of reversing relay 6 which reverses the trunk conductors 3 and 4 back to normal. The visual busy signal in front of the wire chief is now extinguished.

The wire chief may now make whatever tests he deems necessary on the trunk line X, but since the present invention is not particularly concerned with them they will not be described here.

In case the wire chief finds that the trunk line X tests O. K. he may decide to test the line switch C' also to determine whether or not the said line switch is working properly and to ascertain whether or not he is able to call in to the main exchange from the branch exchange by way of the trunk line X. With the assumption as above noted, the wire chief may perform certain operations with the result that direct ground is placed on trunk conductor 4 of the test distributor repeater F and the trunk conductor 3 is left open. With this condition existing, line relay 7 is maintained energized but line relay 9 deenergizes and at armature 31 places ground on trunk conductor 68 of connector H by way of armatures 34 and 40, thereby short circuiting line relay 153 of the test connector H. Upon deenergizing, line relay 153 removes ground from release trunk conductor 183 at armature 164, whereupon switching relay 184 of the line switch C' deenergizes and connects up line relay 185 to the upper conductor of the trunk line X at armature 186, and at armature 187 places

ground on the lower conductor of the said trunk line.

The wire chief now places a bridge including a calling device across the heavy test conductors, thereby closing a circuit of line relay 185 of line switch C' and the said relay, upon energizing, closes the circuit of the stepping magnet and switching relay in series and connects up the test wiper 189 to a point between the two. The line switch C' now operates in the well known manner to select an idle trunk line extending to a connector selector. As soon as an idle trunk line is found switching relay 184 energizes and extends the connection through to the before mentioned connector selector, whereupon the line and release relays energize and the latter prepares the switch for operation and closes a holding circuit for line switch C' in the usual manner. After the operations have proceeded thus far the wire chief may connect the trunk conductors 3 and 4 of the test distributor repeater F together again and remove the ground potential from the latter. When this is done line relay 9 energizes and at armature 31 removes ground from trunk conductor 68 of the test connector H. Line relay 153 of the test connector H now energizes and places a multiple ground on the release trunk conductor 183 at armature 164.

The wire chief may now operate his calling device and extend the connection through the regular trunking system from the branch exchange to the main exchange and thence through the main exchange switches to a telephone located at his desk and in this manner determine whether or not he is able to call in to the branch exchange over the trunk line X and out again.

We shall assume now that after having tested the trunk line X the wire chief decides to test another trunk line between the main and the same branch exchange. Since the trunk line X terminates in the first set of contacts in the bank of the test connector H he may operate his calling device in accordance with the proper digit and cause the wipers of the said test connector to be stepped around into engagement with the desired set of contacts. At the same time that the test connector H is being stepped around the trunk busying switch D in the main exchange is operated to connect with the release trunk conductor of the called trunk line so as to make the called trunk line busy and remove the normal battery and ground connections in the line switch in the main exchange. The test for busy at the end of the rotary movement is the same in this case as it was when the connection was extended to the trunk line X and accordingly need not be described.

As before pointed out the test connector

H in the first nine levels has access to subscribers' lines that terminate in the branch exchange and the wire chief may test one of these lines in the same manner as he tests a trunk line such as trunk line X, after having called the proper digits so as to bring the wipers of the connector H into engagement with the desired set of contacts. Now it will happen many times that a wire chief will wish to test a line which terminates in another level, immediately after having tested a line or a trunk line that terminates in one level. When this occurs it is not necessary for the entire connection to be released but the wire chief may release only the trunk busying switch D and the test connector H. In order to do this the wire chief places battery on the trunk conductor 3 leading to the test distributor repeater F and opens the trunk conductor 4. With this condition existing line relay 9 is maintained energized and line relay 7 is deenergized. Upon deenergizing, line relay 7 opens the circuit of repeating relay 12 at armature 28, the circuit of release relay 8, however, being closed through the working contact of armature 29 and the said armature, and armature 31 and its working contact. Repeating relay 12, upon deenergizing, opens the circuit of control relay 75 of the trunk busying switch D at armature 35 and at armature 36 opens the bridge across trunk conductors 68 and 69 whereupon line relays 151 and 165 of the test connector H deenergize. The trunk busying switch D and the test connector H are now restored to normal position in a manner to be explained more fully hereinafter. With the trunk busying switch D and the test connector thus restored to normal position, the wire chief may restore the loop across trunk conductors 3 and 4, disconnect battery from the latter, and operate his calling device in accordance with the proper digits, and thereby cause the said switches to connect with the desired set of bank contacts.

It may be said at this time that the first nine levels of bank contacts in the trunk busying switch D may ordinarily be omitted as the main to branch exchange trunk lines are seldom terminated in any level other than the tenth. It may be pointed out also at this time that the reason for making the line relay 9 of the test distributor repeater F slow to deenergize is to prevent it from falling back and placing ground on trunk conductor 68 at the beginning of a series of impulses after the connection has been extended to a test connector, such as test connector H. The slow acting line relay 9, however, may fall back before the series of impulses is finished but prior to this time slow acting relay 11, which is energized throughout the series of interruptions has

energized and disconnected the resting contact of armature 31. In the event that line relay 9 does deenergize during the series of interruptions it is energized again at the end of the series before slow acting relay 11 has had time to deenergize.

After having finished making the desired tests the wire chief removes the bridge from across the trunk conductors 3 and 4 of the test distributor repeater F, whereupon line relays 7 and 9 deenergize. Line relay 7, upon deenergizing, opens the circuit of repeating relay 12 at armature 28 and the said relay 12, upon deenergizing, opens the circuit of control relay 75 of the trunk busying switch D at armature 35 and at armature 36 opens the bridge across conductors 68 and 69 of the trunk line extending to the test connector H.

In the test connector H line relays 151 and 153 now deenergize and the latter removes the ground potential from test wiper 178 at armature 164, whereupon the branch exchange end of the trunk line X tests busy no longer. Line relay 151, upon deenergizing, opens the circuit of release relay 152 and completes the circuit of rotary magnet 175 and the wipers are stepped around to the next contact set. Release relay 152, upon deenergizing, opens the circuit of the rotary magnet and completes the following circuit for release magnet 165: from ground by way of armature 159 and its resting contact, armature 163 and its resting contact, release link spring 160 and its working contact, and release magnet 165 to battery. Release magnet 165, upon energizing, forces the double dog 162 out of engagement with the shaft of the switch (not shown) whereupon the release link 161 moves downward over the end of the double dog in the manner shown, thereby retaining the said dog in place. As soon as the release link 161 moves downward, the circuit of the release magnet 165 is opened and the following circuit is closed: from ground by way of release link spring 160 and its resting contact, off normal contacts 170, and slow acting relay 197 to battery. The switch shaft which is released as soon as the double dog 162 is forced out of engagement with it, now returns to normal position and opens the circuit of slow acting relay 197 at off normal contacts 170. Relay 197 is made slightly slow acting so as to insure that its armature makes a full stroke in all cases. This is necessary as the off normal springs are opened very shortly after the release link spring 160 closes the circuit of slow acting relay 197 by coming into engagement with its own resting contact. It is seen that in any event the circuit of slow acting relay 197 is closed only momentarily when the switch is functioning properly. Upon energizing, relay 197 closes at armature 196 throughout the series of interruptions has

a circuit for the meter M and the slow set SS in multiple. The magnet of the meter M now becomes energized and the number wheels are advanced to register the call and 5 the slow set SS begins to operate to force the spring 198 into engagement with its working contact but does not have time to do so in case the switch H is releasing properly. Relay 197, upon deenergizing, opens 10 the circuit of meter M and the slow set SS at armature 196 whereupon the magnet of the meter M becomes deenergized and the associated pawl is caused to engage another notch on the number wheel, and the solenoid 15 of the slow set SS, upon deenergizing, allows the dash pot arrangement to restore to normal position immediately.

The function of the meter M is to register the number of both completed and attempted calls, and it will obviously do so since it operates each time that any switch in the branch exchange is released, it being understood of course that the conductor extending to slow acting relay 197 is common 20 to the test connector H and the regular connector selectors in the branch exchange.

In case the test connector H becomes mechanically stuck and does not release immediately the circuit of slow acting relay 25 197 is maintained closed for a longer period of time than is usual and the circuit of the solenoid of the slow set SS is consequently maintained closed long enough to allow the dash pot arrangement to be operated to 30 force the spring 198 into engagement with its associated contact, thereby closing a circuit for the buzzer 199 so as to notify an attendant. It will be noted, however, that the circuit of the release magnet 165 is 35 opened just as soon as the release link 161 has dropped over the end of the double dog 162 and consequently the said release magnet, which is generally low wound so as to give it the necessary power, does not burn 40 out or become hot, as has heretofore been the case, when the switch shaft remains stuck.

To continue with the description of the 45 release of the connection, the test connector H in the branch exchange is now restored to normal position, the guarding ground potential is removed from release conductor 183 of the trunk line X, and the completed call has been registered on the meter M. In 50 the meantime the switches D and F in the main exchange have been restored to normal position as will be explained now. Line relay 7 of the test distributor repeater F, upon deenergizing, not only opens the circuit of repeating relay 12 as explained, but 55 also opens the circuit of release relay 8 and closes the previously traced circuit for slow acting relay 11. Slow acting relay 11 becomes energized but does not have any particular function at this time. Release relay 60

8, upon deenergizing, opens the circuit of slow acting relay 11, closes a circuit for release magnet 15 by way of armature 27 and its resting contact, armature 30 and its resting contact, and release link spring 20 and 65 its working contact. Upon energizing, release magnet 15 forces the double dog 18 out of engagement with the switch shaft, whereupon release link 19 drops over the end of said double dog 18 thereby retaining 70 the said dog in place. The release link spring 20 moves downward at this time and opens the circuit of release magnet 15 and extends the circuit to the off normal spring 21 and its associated contact. The conductor extending from the contact associated with the off normal spring 21 is assumed to extend to a slow relay such as the slow relay 197, Fig. 2, with which there 75 is associated the same type of equipment as is associated with the slow acting relay 197. The shaft and wipers of the test distributor repeater F are now restored to normal position, the circuit of the associated slow acting relay being opened at off normal contacts 21 by the switch shaft when it reaches 80 normal position.

Control relay 75 of the trunk busying switch D, upon deenergizing, in response to the opening of its circuit at armature 35 85 of repeating relay 12 of switch F, opens the circuit of release relay 76 at armature 86, and closes the previously traced circuit for slow acting relay 78 and rotary magnet 81. Rotary magnet 81, upon energizing, advances the switch wiper 95 into engagement with the next contact. Relay 78 energizes, but does not have any particular function at this time. Relay 76, upon deenergizing, 90 opens the circuit of relay 78 and rotary magnet 81 at armature 88 and closes the circuit of the release magnet 82 by way of release link spring 85 and its working contact. Release magnet 82, upon energizing, 95 forces the double dog 83 out of engagement 100 with the switch shaft, whereupon release link 84 drops over the end of the said double dog, thereby retaining it in place. Release link spring 85, upon moving downward at 105 this time opens the circuit of release magnet 82 and closes the circuit of the slow acting relay which is assumed to be associated with the off normal contact 93. The shaft and wiper of the switch D are now 110 restored to normal position in the usual manner, the circuit of the slow acting relay associated with off normal contact 93 being opened by the switch shaft at the said off normal contact as soon as the said shaft reaches normal position. The entire connection is now released and is ready for any 115 subsequent calls which the wire chief may desire to make.

The various features of the invention, 120 having been thus described and ascertained,

will now be pointed out in the appended claims.

What I claim as my invention is:

1. In a telephone system, a main exchange and a branch exchange, a plurality of two way two conductor trunk lines connecting said exchanges, a wire chief's testing trunk connecting said exchanges, a test switch in the branch exchange for connecting said test trunk with any one of said two way trunk lines, means for clearing the selected trunk for testing at the branch exchange end thereof when the connection is established, and means operating automatically at the same time for clearing the selected trunk at the main exchange end thereof.

2. In a telephone system, a two way trunk line extending between distant exchanges, a normally closed relay bridge across the trunk line at each exchange, a test switch for use by a wire chief in setting up a testing connection with said trunk line, and means operated independent of control over the trunk line when the testing connection is established for opening both relay bridges to permit the trunk line to be tested.

3. In a telephone system, a two way trunk line extending between distant exchanges, a normally closed relay bridge across the trunk line at each exchange, wire chief's testing equipment in the first exchange, means including a test switch in the second exchange for setting up a testing connection with said trunk line, an auxiliary switch in the first exchange operated simultaneously with said test switch, and means controlled by said switches for opening both relay bridges when the testing connection is established.

4. In a telephone system, a two way trunk line extending between two exchanges and terminating at each exchange in an automatic switch, a line relay in each switch normally connected in bridge of said trunk line, another switch for connecting with said trunk line in one exchange, and means effective when the trunk line is connected with and while the associated switches are at normal for disconnecting both said line relays to prevent the operation of the associated switches.

5. In a telephone system, a two way trunk line extending between two exchanges and terminating at each exchange in an automatic switch, a line relay in each switch normally connected in bridge of said trunk line, a third switch for connecting with said trunk line in the first exchange, means for disconnecting the line relay in the first exchange when the trunk line is connected with, a fourth switch in the second exchange, operating simultaneously with said third switch, means controlled by said fourth switch for disconnecting the other line relay and means for causing said third and

fourth switches to operate simultaneously as set forth.

6. In a telephone system, a two way trunk line, a normally closed relay bridge across said trunk line at both ends, the relay at either end being normally responsive when the trunk line is taken for use at the other end in the process of setting up a talking connection, testing means for connecting with said trunk line at one end, and means for opening both bridges when the trunk line is connected with, by said testing means, while preventing the relays in said bridges from operating.

7. In a telephone system, a two way trunk line connecting two exchanges, a normally closed relay bridge across said trunk line at both ends, a relay in each bridge normally operated when the trunk line is connected with at the other exchange, means at each exchange for establishing such connections, additional means in one exchange for connecting with said trunk line, the relays in both bridges remaining inoperative, and means for opening both bridges when the trunk line is connected with.

8. In a telephone system, a two way trunk line extending between distant exchanges, automatic trunking switches in both exchanges having access to said trunk line, a wire chief's test switch in one exchange also having access to said trunk line, and means operative independent of current flow over said trunk line whenever the said trunk line is connected with by way of said test switch for rendering the trunk line busy to the said trunking switches.

9. In a telephone system, a trunk line terminating in an automatic switch, means for connecting with said trunk over one path, means responsive to such connection for operating said switch, means for connecting with said trunk line at the same end over another path after the first connection is released, and means actuated automatically during the establishment of the second connection for preventing the operation of said switch.

10. In a telephone system, a trunk line, two automatic switches, contacts in the banks of said switches assigned to the two ends of said trunk line, respectively, and a single directly controlled impulse transmitting device for operating said switches in synchronism to select said contacts simultaneously.

11. In a telephone system, a trunk line, two automatic switches, contacts in the banks of said switches assigned to the two ends of said trunk line, respectively, a single device for operating said switches in synchronism to select said contacts simultaneously, a cut-off relay at one end of said trunk line controlled via one of said contacts, and a cut-off relay at the other end of said trunk line

controlled over the other of said contacts.

12. In a telephone system, an automatic switch, a trunk line accessible to said switch and terminating in a second switch, a second 5 trunk line accessible to said second switch, means for operating said switches successively to extend a connection to said second trunk line, an auxiliary switch inactive while the first switch is being operated, means in 10 the first switch for operating the auxiliary switch simultaneously with the second switch, and a contact in the bank of said auxiliary switch assigned to said second trunk line.

15 13. In a testing system for trunk lines, a plurality of serially related switches for selecting a trunk line at the remote end thereof, an auxiliary switch for selecting the same trunk line at the near end thereof, and 20 means for operating said last switch in synchronism with the final switch of said plurality.

14. In a testing system for trunk lines, a plurality of serially related switches for 25 selecting a trunk line at the remote end thereof, an auxiliary switch for selecting the same trunk line at the near end thereof, means for operating said last switch in synchronism with the final switch of said plurality, a testing circuit including said plurality of switches, and means for clearing the trunk line for testing controlled by said auxiliary switch.

30 15. In a telephone system, two automatic switches in serial relation, an auxiliary switch individual to said first switch, a line relay for operating said first switch to connect with said second switch, a second line relay controlled by said first line relay, control circuits for said second switch and said auxiliary switch controlled by said second line relay, and means responsive to the completion of said connection for closing said circuits.

45 16. In a telephone testing system, groups of trunks, test connectors having access to said trunks over bank contacts individual to said trunks, each test connector having access to only a particular one of said groups, 50 a test distributor having access to all of said test connectors, a trunk busying switch associated with said test distributor having access to bank contacts each of which is common to a corresponding guarding conductor in each of said groups of trunks but normally disconnected therefrom, means for operating said test distributor to seize one of said test connectors and to connect the common bank contacts to corresponding 55 guarding conductors of the group of trunks to which the seized connector has access, and means for operating the seized test connector and said switch to seize and busy over said contacts any one of said trunks in

the group to which the said connector has 65 access.

17. In a telephone testing system, groups of trunk lines, said trunks terminating at one end in bank contacts individual thereto, test connectors having access to said bank 70 contacts for testing purposes, said trunks having guarding conductors at the other end, bank contacts common to all said guarding conductors but normally disconnected therefrom, an auxiliary switch having 75 access to said common bank contacts, means for connecting the guarding conductors of any one of said groups of trunks to said bank contacts to the exclusion of the other groups of guarding conductors, and 80 means for operating said test connectors and said auxiliary switch to seize said trunks and to make the seized trunks busy at both ends.

18. In a telephone system, a main exchange, a plurality of branch exchanges, a group of trunk lines connecting each branch exchange with said main exchange, guarding conductors for all of said trunk lines at the main exchange, a trunk busying switch 90 at the main exchange, a level of bank contacts in said switch, said level common to all of said guarding conductors but normally disconnected therefrom, and means whereby 95 the guarding conductors of any one of said groups of trunk lines may be connected to said level of bank contacts to the exclusion of the other groups of guarding conductors.

19. In a telephone testing system, groups 100 of trunks, a trunk busying switch, bank contacts accessible to said switch, the first of said contacts being common to the first of said trunks in each of said groups but normally disconnected therefrom, and means for connecting said first contact with the first trunk in any one of said groups without connecting the first contact to the first trunk in the remaining groups.

20. In a telephone testing system, groups 105 of trunks, a trunk busying switch, bank contacts accessible to said switch, the first of said contacts being common to the first of said trunks in each of said groups but normally disconnected therefrom, means for connecting said first contact with the first trunk in any one of said groups without connecting the first contact to the first trunk in the remaining groups, and means for operating said switch to connect with said first contact to busy whichever first trunk 110 the contact may be connected to.

21. In a telephone testing system, groups 115 of trunks, a trunk busying switch, bank contacts in said switch, each of said contacts being common to a corresponding trunk in each of said groups but normally disconnected therefrom, and means for connecting said contacts with corresponding trunks of

any one of said groups without connecting said contacts to corresponding trunks of the remaining groups.

22. In a telephone testing system, groups of trunks, a trunk busying switch, bank contacts in said switch, each of said contacts being common to a corresponding trunk in each of said groups but normally disconnected therefrom, means for connecting said contacts with corresponding trunks of any

one of said groups without connecting said contacts to corresponding trunks of the remaining groups and means for operating said switch to connect with any one of said contacts to busy whichever trunk the said one contact is connected with. 15

In witness whereof, I hereunto subscribe my name this 29th day of August, A. D., 1921.

CLARENCE ERNEST LOMAX.
